UNITED STATES PATENT OFFICE.

CARL AUGENSTEIN, OF CRANSTON, RHODE ISLAND, ASSIGNOR TO AUTOMATIC GOLD CHAIN COMPANY, A FIRM COMPRISING EDWIN F. M. SPEIDEL AND ALBERT R. SPEIDEL, BOTH OF EDGEWOOD, RHODE ISLAND.

BRACELET HOOK.

Application filed December 10, 1926. Serial No. 153,973.

- This invention relates to bracelet hooks, and has for its object to provide a hook of this character more particularly for removably attaching the ends of a bracelet to a wrist watch, the improved hook being of the extensible variety so as to permit the general stretch or extensibility of the bracelet unit to be increased to facilitate its being passed over the hand of the wearer.
- 10 A further object of the invention is the provision of a bracelet hook comprising a body member and a hook member having a portion slidable in the body member, the hook having a closing tongue locked closed when the members are in contracted position and released to be opened when the members are in extended position with a spring arranged to act between said members to press them toward contracted position.
- 15 20 With these and other objects in view, the invention consists of certain novel features of construction, as will be more fully described and particularly pointed out in the appended claims.
- 25 In the accompanying drawings:

Figure 1 is a front view showing the hook as attaching the end of a bracelet to a wrist watch.

Figure 2 is a perspective view showing the under side of the body member of the hook.

Figure 3 is a section on line 3—3 of Figure 2.

Figure 4 is a perspective view showing the band shaped hook portion of the bracelet hook.

Figure 5 is a sectional side view on line 5—5 of Figure 4.

Figure 6 is a sectional top view showing the hook member as slidably mounted in its body member.

Figure 7 is a central sectional elevation showing the shank portion of the hook member as housed in the body member with springs acting between the two members to press them toward closed position.

Figure 8 shows the hook member as extending beyond the body member with the spring compressed to permit the resilient arm of the hook to be compressed.

Figure 9 is a side elevation showing the hook extended from its body portion and with the tongue depressed into position to engage the bail of the wrist watch.

It is found in practice of advantage to attach hooks to the ends of an extensible watch bracelet for detachably connecting the bracelet to a wrist watch or the like and to also form these hooks extensible to cooperate with the other links of the bracelet to increase the extensible length thereof, to facilitate its being passed over the hand of the wearer and it is also found of advantage to so arrange the bracelet hook that its closing tongue is locked against being opened except when the hook units are in extended position, a spring being provided for pressing the members of the hook unit toward contracted position; and the following is a detailed description of the present embodiment of the invention showing one arrangement by which the desired result may be accomplished.

The body member 10 of this bracelet hook is preferably formed from a blank of sheet stock providing a front plate 11 with side portions folded to form the side wall 12 and its edges turned inwardly to form portions 13 of a bottom wall and the edges of these portions being folded inwardly at 14 to provide a longitudinal space 15 in the back of the body member in which the spring presently described, is guided.

One end of these side walls 12 is provided with inturned members 16 to provide an attaching cross bar on the body member and the bottom wall portions of this body member are herein shown as being provided with lateral extensions 17 which are folded into position to extend through between the arms 18 of the hook member, for the purpose presently described.

Mounted to slide in this body member is a hook member 18 which is preferably formed of a strip of sheet stock into elongated band shape having a relatively broad front arm 19, one end of which is bent to form a hook 20, and a relatively narrow arm 21 is connected to the broader arm by a bridge 22. The forward end of the narrower arm is arranged to extend under the hook as at 23 to prevent the hook from being opened outwardly.

The shank portion of this hook member is arranged to slide into the body member and the resilient arm 21 thereof is arranged to be positioned in the space 15 between the bottom wall portions 13 of this body member

to close this opening and so complete this bottom wall, the broader arm 19 being arranged to slide beneath the inturned edges 14 and between the side walls 12 of the body member, and this hook portion is of a length considerably greater than that of the body member so that the hook portion will extend a substantial distance beyond the body member, the folded shank portion only of the hook being housed in the body.

In assembling the parts the shank portion of the hook is positioned in the body member, the spring 24 is positioned in the shank member, its rear end abutting the bridge portion thereof and the forward end of this spring being compressed and the abutment arms 17 are turned inwardly to serve as an abutment for the other end of the spring causing it to press the hook member into the housing member, whereby the abutment arms serve a double purpose, first, to hold the spring under compression; and second, to fit closely between the arms of the hook to prevent the resilient arm thereof from being depressed while these hook members are in contracted position. Therefore, in order to permit this resilient arm 21 to be compressed for the purpose of opening the hook, it is necessary to extend the hook members relatively into the position illustrated in Figures 8 and 9 of the drawing, whereby the tongue may be depressed and so open the hook to be attached to the bail of a watch or other desired object.

My improved extensible hook is capable of the maximum extension and so serves to co-operate with the extensible links of the bracelet to considerably elongate the whole and at the same time the hook is locked against inadvertent opening except when the hook is in extended position.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

50 1. An extensible bracelet hook comprising a casing member, a hook member having a shank portion slideable in said casing and having a hook portion extending a substantial distance beyond the casing, a hook-closing tongue carried by the hook member and locked closed when the members are relatively contracted and released when said members are in extended position.

60 2. An extensible bracelet hook comprising a body member formed of sheet stock, a hook member having a shank portion slideable in said body member and having a hook portion extending a substantial distance beyond said body, a tongue for closing the

hook, means for locking the tongue closed 65 when the members are contracted, and a spring acting to press said members toward contracted position.

3. An extensible bracelet link comprising a guide member, a hook member having a shank portion slideable in the guide member and having an enlarged hook portion extending a substantial distance beyond the guide member, a resilient tongue for closing the hook, a stop for preventing the tongue 70 from being compressed when the members are in contracted position, and a spring acting to press said members toward contracted position. 75

4. An extensible bracelet hook comprising a body member, a hook member formed of elongated band shape having a shank portion slideable in said body and having a hook-shaped portion extending a substantial 80 distance beyond said body, a spring acting between said members to press them toward contracted position, and means for preventing the hook from being opened except when in extended position.

5. An extensible bracelet link comprising a guide member formed of sheet stock and having a broad front face and side walls, a hook member having a shank portion slideable in the guide member and having an enlarged hook portion extending a substantial 90 distance beyond the guide member, said extending portion having a front face substantially flush with the plane of the front face of its guide member, a resilient tongue for closing the hook, a stop for preventing the tongue from being compressed when the members are in contracted position and a spring acting to press said members toward contracted position. 95

6. An extensible bracelet hook comprising 100 a casing member formed of sheet stock folded to provide front, side and rear walls, a hook member formed of a strip of metal folded into elongated band shape having a shank portion slideable in said casing member 105 and having a hook portion extending a substantial distance beyond its casing, the front arm of the band being formed in hook shape and the rear arm forms a resilient closing tongue and members carried by the casing 110 extending between said arms to prevent them from being depressed to open the hook except when in extended position, and a spring acting to press said members toward contracted position. 115

7. An expansion catch comprising two members of sheet metal bent upon themselves and having openings permitting one member to slide within the other, one member comprising a hook and a catch therefor, and the other member a lock for said catch. 120

In testimony whereof I affix my signature,
CARL AUGENSTEIN.
